BOOSTER AFT SHOE LATCHING MECHANISM
 Richard C. Wilson, Champlin, Minn., assignor, by mesne assignments, to the United States of America as represented by the Secretary of the Navy
 Original application Oct. 22, 1959, Ser. No. 848,163.
 Divided and this application Dec. 31, 1959, Ser. No. 863,367

3 Claims. (Cl. 89—1.7)

This invention relates generally to missile weapon launching apparatus and more particularly it pertains to an aft booster shoe latching arrangement for releasably engaging a missile weapon with the launcher of a guided missile launching system.

This patent application is a division of U.S. patent application Serial Number 848,163, entitled "Guided Missile Launching System," filed on October 22, 1959, by Myron J. Bauer et al.

In booster assisted launching of missiles or aircraft from zero length launchers, it is necessary to delay their release until the thrust of the booster is adequate for flight of the missile weapon. In addition, because the launcher guide usually is aimed at any angle including the vertical, adequate support must be provided for the missile weapon or aircraft together with a quick release action thereof.

It is accordingly an object of this invention to provide a lug receiving and retaining pawl for a missile weapon which cooperates with a restraining lug on a launcher.

Another object of this invention is to provide a restraining pawl for a missile weapon launcher which incorporates a predetermined thrust release.

Another object of this invention is to provide an arrangement for transferring engagement of a missile weapon handling lug from a first set of pawls to a second set of pawls.

And another object of this invention is to provide a lug presence sensing mechanism for a lug engagement mechanism.

Still another object of this invention is to provide a heavy toggle cocking and release pawl mechanism having buffering action.

And still yet another object of this invention is to provide a safety latch for a booster lug retaining latch of a missile weapon.

These and other objects and attendant advantages of this invention will become more readily apparent and understood from the following detailed specification and accompanying drawings in which:

FIG. 1. is a side elevation, with parts removed, of a guided missile launcher with a weapon positioned thereon;

FIG. 2 is a longitudinal cross section of the rear portion of a launcher guide arm;

FIG. 3 is a dimetric view of a saddle cart and pawl linkage therefor showing relationship to tracks of a loader;

FIG. 4 is a dimetric view of a guide arm latch and saddle cart;

FIG. 5 is an operational schematic of the guide arm latching mechanism ready for loading of a missile weapon;

FIG. 5a is a section taken of the forward latch links showing details of the locking detent when the mechanism is positioned as in FIG. 5;

FIG. 6 is an operational schematic of the guide arm latching mechanism with the missile weapon loaded to the guide arm;

FIG. 6a is a section taken of the forward latch links showing details of the locking detent when the mechanism is positioned as in FIG. 6;

2

FIG. 7 is an operational schematic of the guide arm latching mechanism with the missile weapon latched to the guide arm;

FIG. 7a is a section taken of the forward latch links showing details of the locking detent when the mechanism is positioned as in FIG. 7;

FIG. 8 is an operational schematic of the guide arm latching mechanism with the missile weapon in the ready-to-fire position;

FIG. 8a is a section taken of the forward latch links showing details of the locking detent when the mechanism is positioned as in FIG. 8;

FIG. 9 is an operational schematic of the guide arm latching mechanism with the missile weapon after three-sixteenths inch of guided travel;

FIG. 9a is a section taken of the forward latch links showing details of the locking detent when the mechanism is positioned as in FIG. 9;

FIG. 10 is an operational schematic of the guide arm latching mechanism with the missile weapon after five and one-half inches of guided travel; and

FIG. 11 is an operational schematic of the guide arm latching mechanism with the missile weapon at end of guided travel.

FIG. 11a is a section taken of the forward latch links showing details of the locking detent when the mechanism is positioned as in FIG. 11.

Referring now to FIG. 1, there is shown a launcher 5000, which is part of a guided missile launching system referred to in the above mentioned patent application. The launcher 5000 is provided with a pair of guide arms 5002, and a carriage 5016. The launcher 5000 may be trained in a horizontal plane by rotating the carriage 5016, and elevated in a vertical plane by means of a trunnion tube 5008 upon which the guide arms 5002 are pivoted. A missile weapon 400, consisting of a missile 100 and a booster 200 is shown supported upon a launcher rail 5010 of the guide arm 5002.

After being equipped with wings 102 and fins 104 for missile 100, and fins 208 for the booster 200 elsewhere, the weapon 400 is transported over a span track 4001 temporarily joined to the aft end of the guide arm 5002, shown in FIG. 2.

The booster 200 of the weapon 400 has a wide forward booster shoe, not shown, which slides upon the launcher rail 5010 and a narrow aft upper booster shoe 204. The weight of the missile weapon 400 is so distributed that this aft booster shoe 204 thrusts upwardly and provides no support but only a thrust guide and locking means therefor.

FIG. 5 is an operational schematic of the guide arm latching mechanism ready for loading of a missile weapon 400. The missile weapon 400 is pushed to its desired location on the launcher rail 5010 by a saddle cart 2006, shown in FIG. 3. A plurality of vertical and horizontal rollers 2058 and 2060, respectively, adapted for skid tracks 2048 and 2050, enable the narrow aft upper booster shoe 204 to be guided by the wide launcher rail 5010. In the saddle cart 2006, a pair of articulated pawls, namely a reverse or aft motion pawl 2005 and a forward motion pawl 2007, retain and push, respectively, the aft booster shoe 204 therebetween.

In location on the guide arm 5002, the missile weapon 400 is released by the saddle cart 2006 which then withdraws from the launcher rail 5010. The saddle cart 2006 is shown in FIG. 4 relinquishing the aft upper booster shoe 204 to a forward motion restraining latch 5113 and a reverse motion latch 5160 of an aft shoe latching mechanism 5110.

The aft shoe latching mechanism 5110, shown in FIG. 2 and illustrated in detail in FIGS. 5 through 11, receives the aft upper booster shoe 204 from the loader saddle cart 2006 and retains the missile weapon 400 in a position for firing on the launcher guide arm 5002.

The aft shoe latching mechanism 5110 is mounted near the aft end of the guide arm 5002. The bottom of the launcher guide arm 5002 contains a rectangular opening for the latching mechanism 5110. Near the bottom of a housing 5112 for the latching mechanism, a peripheral flange 5114 extends to mount the aft shoe latching mechanism 5110 to the bottom of the launcher guide arm 5002.

The basic unit of the aft shoe latching mechanism 5110 is the previously mentioned latch housing 5112, as shown in FIGS. 5 to 11. One side of the latch housing 5112 is provided with a removable latch housing cover (not shown). Warm fluid is circulated through both the latch housing 5112 and the cover therefor to prevent ice from forming.

A restraining motion spring 5116 restricts the rotation of a forward motion restraining latch 5118. The forward motion restraining latch 5118 is provided to engage the front of the booster aft shoe 204 and prevent the missile weapon 400 from shifting forward on the guide arm 5002.

When the booster 200 of the missile weapon 400 is fired and the forward thrust is approximately 10,000 pounds, the forward motion restraining latch 5118 rotates, compressing the restraining motion spring 5116 until a pair of pivotally joined forward latch links 5120 and 5122 go over center and collapse. The aft shoe 204 of the booster 200 is thereby released and the restraining motion spring 5116 returns to its normal position.

A buffer piston 5124 restricts the return of the restraining motion spring 5116 after the missile weapon 400 is fired and the forward latch links 5120 and 5122 have gone over center and collapsed.

When the buffer piston 5124 is moved upwardly, a check valve 5126 in the piston 5124 opens, permitting oil to flow from the top to the bottom thereof through drilled passages and the check valve 5126. On the return stroke, the check valve 5126 is seated and the buffer piston 5124 buffs the restraining spring recoil by the oil returning to the top of the piston through clearance between the piston 5124 and the cylinder wall of the check valve 5126. The buffer piston 5124 is a smooth cylinder which has no oil grooves. A piston shaft 5128 extends from the top of the buffer piston 5124.

A rocker arm 5130 drives the forward latch links 5120 and 5122 into the overcenter position when the reverse motion latch 5160 for the aft booster shoe 204 is raised. A pin 5132 holds one end of the rocker arm 5130 to a reverse motion latch piston 5178, and a second pin 5133 holds the other end of the rocker arm 5130 to a forward latch link clevis 5134. As the reverse motion latch 5160 raises, an adjusting screw 5136 in the rocker arm 5130 pivots against a cam 5138, forcing the forward latch links 5120 and 5122 over center.

The link clevis 5134 in a connecting link between the rocker arm 5130 and the upper forward latch link 5120. When the reverse motion latch 5160 is raised, the rocker arm 5130 pivots, swinging the end of link clevis 5134 in a small arc. When the rocker arm 5130 is at the greatest distance in the path of its arc, the link clevis 5134 pushes the forward latch links 5120 and 5122 over center, as best shown in FIG. 5.

A forward latch links cam 5140 is provided to force the forward latch links 5120 and 5122 over center when the forward motion restraining latch 5118 pushes the forward latch links 5120 and 5122 upwardly. The forward latch link cam 5140 is a pyramid shaped structure which is secured to the latch housing 5112, as shown in FIG. 5.

A differential link 5142 lifts a swivel track 5144 after the guide arm 5002 is loaded with a weapon 400 and the reverse motion latch 5160 is lowered, as shown best in FIG. 8. During the loading cycle of the weapon 400, the aft booster shoe 204 is positioned below a pair of shoe indicator plungers 5152, as shown in FIG. 8. The reverse motion latch 5160 is then lowered by the reverse motion latch piston 5178. Upon lowering the reverse

motion latch, the differential link 5142 is caused to rotate clockwise. This rotation, acting on a differential transfer clevis 5148 and a track toggle link 5150, lifts the swivel track 5144, shown raised in FIG. 8.

5 A differential pivot 5146 lifts the shoe indicator plungers 5152 for the aft booster shoe 204 when the reverse motion latch 5160 is lifted, thus supporting and providing a pivot for the differential link 5142.

A spring-loaded forward latch detent 5154, shown best FIG. 5a, holds the forward latch links 5120 and 5122 over center. Only in the overcenter position is the forward motion restraining latch 5118 capable of restraining the forward motion of the weapon 400. When the reverse motion latch 5160 is raised, the rocker arm 5130 pivots against cam 5138 and forces the forward latch links 5120 and 5122 over center.

A boss 5156, as shown FIG. 5a, on the upper latch link 5120 strikes the latch detent 5154. The detent 5154 is mounted at an approximately sixty (60) degree angle with respect to the front of the housing 5112. As the upper latch link 5120 moves against the detent 5154, it moves inward at a sixty (60) degree angle.

When the upper forward latch link 5120 passes a predetermined point, the detent 5154 slides over the forward latch link and the link 5120 is locked over center. When the forward motion restraining latch 5118 is pushed forwardly, the forward latch links 5120 and 5122 are pushed upwardly to compress the restraining motion spring 5116. As the upper latch link 5120 rises, it clears the detent 5154 and it is forced over center by the forward latch link cam 5140. This action is shown consecutively in FIGS. 5 to 11a.

The two shoe indicator plungers 5152, spring-loaded to the extend position, release a reverse motion safety latch 5158. The indicator plungers 5152 are lifted by the reverse motion latch 5160 before loading of the weapon 400. After the reverse motion latch 5160 is lowered, the indicator plungers 5152 rest on top of the aft booster shoe 204. When the booster 200 of the weapon 400 is fired, the indicator plungers 5152 extend. This rotates the differential link 5142 and releases the safety latch 5158, as shown in FIG. 7.

Two latch blocks 5182 are provided which form a reinforcing frame on the right and left side of the latch housing 5112 to support a pivot pin 5184 for the forward motion restraining latch 5118, the shoe indicator plungers 5152 and the forward latch detent 5154.

The forward motion restraining latch 5118 engages the front of the booster aft shoe 204 and prevents the weapon 400 from shifting ahead on the launcher guide arm 5002 until the booster 200 is fired. When the booster 200 of the missile weapon 400 is fired, the thrust of the booster 200 swings the forward motion restraining latch 5118 forward, allowing the aft booster shoe 204 to clear the latch. The forward motion restraining latch 5118 resembles a tuning fork which is mounted by the handle and has an area between the forks for the forward motion pawl 2007, shown in FIG. 6, to slide through when the saddle cart 2006 is moved in.

60 The reverse motion latch 5160 slides in back of the booster aft shoe 204 when the weapon 400 is loaded to the guide arm 5002. The reverse motion latch 5160 is an H-shaped steel device. The reverse motion latch 5160 travels at an angle from the vertical. Guided in this manner, the reverse motion latch 5160 actually moves the aft booster shoe 204 forward to wedge in against the restraining force of the forward motion restraining latch 5118, as shown in FIGS. 7 and 8.

The differential transfer clevis 5148 connects the differential link 5142 to the track toggle link 5150 and releases the safety latch 5158 after the booster 200 of the weapon 400 is fired. When the booster aft shoe 204 is in the load position on the guide arm 5002, the reverse motion latch 5160 is lowered in back of the aft booster shoe 204. Lowering of the reverse motion latch 5160 in back of the

aft booster shoe 204 rotates the differential link 5142, which, in turn, pushes the differential transfer clevis 5148 back, and causes the track toggle link 5150 to be rotated, as shown in FIGS. 7 and 8.

After the booster 200 of the missile weapon 400 is fired, the shoe indicator plungers 5152 drop, rotating the differential link 5142 counterclockwise. As the differential link 5142 rotates, the differential transfer clevis 5148 moves forward and an adjusting screw 5164 strikes and releases the safety latch 5158, as shown in FIG. 10.

The safety latch 5158 locks the reverse motion latch 5160 in the extended position when the guide arm 5002 is loaded with the weapon 400 and the saddle cart 2006 of the loader 2002 has returned from the reverse motion latch 5160.

When the shoe indicator plungers 5152 are on top of the booster aft shoe 204 and the reverse motion latch 5160 is lowered, a safety latch spring 5166 tends to lock the safety latch 5158 over the reverse motion latch 5160. However, a chain pawl roller 2235 on the saddle cart forward motion pawl 2007, as shown best in FIG. 7, contacts a pawl indicator link 5168 and holds the safety latch 5158 disengaged.

This safety provision allows the weapon 400 to be unloaded without firing of the booster 200 thereof, if desired. When the loader chain pawl roller 2235 moves away with the saddle cart, the spring-loaded safety latch 5158 snaps over the reverse motion latch 5160. If a weapon 400 is to be unloaded from the launcher guide arm 5002, the loader chain pawl roller 2235 contacts the pawl indicator link 5168 and releases the safety latch 5158.

A safety latch release link 5170, and the adjusting screw 5164 are connecting means between the pawl indicator link 5168 and the safety latch 5158.

The track toggle link 5150 raises and lowers the swivel track 5144. The track toggle link 5150 pivots on a pin 5172. The shuttling of the differential transfer clevis 5148 raises or lowers the swivel track 5144.

The pawl indicator link 5168 releases the safety latch 5158 when the saddle cart 2006 of the loader 2002 is in a position to unload the weapon 400 from the guide arm 5002. When the chain pawl roller 2235 enters the loaded guide arm 5002, the roller 2235 contacts the pawl indicator link 5168 and releases the safety latch 5158.

The swivel track 5144 raises the forward motion pawl 2007 of the saddle cart 2006 over the aft booster shoe 204, allowing the saddle cart 2006 to unlatch from the aft booster shoe 204, as shown in FIG. 7.

A hydraulic actuator piston 5174 supplements the spring force of the shoe indicator plungers 5152 to positively move the differential transfer clevis 5148 forward to release the safety latch 5158 after the booster 200 of the weapon 400 is fired, as shown in FIG. 10.

After the booster shoe 204 is under the shoe indicator plungers 5152, a solenoid-operated directional pilot valve 5036 which is part of a guide arm control 5032 is cycled to lower the aft motion latch 5160. Cycling of the directional pilot valve 5036 applies hydraulic pressure to the top of the reverse motion latch piston 5178 and to the hydraulic actuator piston 5174, as shown best in FIG. 7.

When the reverse motion latch piston 5178 moves downwardly, the differential transfer clevis 5148 moves against the hydraulic actuator piston 5174, pushing the hydraulic actuator piston 5174 inwardly and forcing the oil out against the accumulator pressure.

When the booster 200 of the weapon 400 is fired and the aft booster shoe 204 thereof slides out from under the shoe indicator plungers 5152, the hydraulic pressure against the hydraulic actuator piston 5174 starts the differential transfer clevis 5148 forward. The spring-loaded shoe indicator plungers 5152 snap the differential transfer clevis 5148 forward at the end of the stroke. An orifice (not shown) in the line to the hydraulic actuator piston 5174 slows the piston 5174 down and prevents de-

structive peening of mating parts, as indicated in FIG. 10.

The reverse motion latch piston 5178 raises or lowers the reverse motion latch 5160. The reverse motion piston 5178 extends upwardly to provide actuating means for interlock switches SIRA2 and SIRA3 and downwardly to operate the reverse motion latch 5160, as shown in FIGS. 5, 6, and following FIGS. 7 to 11.

It is to be noted that FIG. 8 illustrates the reverse motion latch 5160 in position behind the aft booster shoe 204. FIG. 9 illustrates the aft shoe latching mechanism after three-sixteenth ($\frac{3}{16}$) inch of travel of the weapon 400, while FIG. 10 shows the aft shoe latching mechanism 5110 after five and one-half ($5\frac{1}{2}$) inches of travel 15 of the aft booster shoe 204 of the weapon 400. FIG. 11 shows the aft shoe latching mechanism 5110 after the aft booster shoe 204 of the weapon 400 has cleared the launcher rail 5010.

As shown in FIGS. 4 and 5, a spring-loaded hydraulically released reversed motion latch detent 5180 is provided to lock the reverse motion latch piston 5178 and the reverse motion latch 5160 in the retract position in the absence of hydraulic fluid pressure as in shut-down.

An operation cycle of the aft motion latching mechanism 5110 during a loading and firing of a missile weapon 400 will now be described in connection with the series of illustrations, FIGS. 5 to 11, inclusive.

As shown in FIG. 5, the aft motion latching mechanism 5110 is ready to receive a missile weapon 400. It will be noted that a solenoid LCRA2 is energized, and it has shifted the directional pilot valve 5036 in the associated guide arm control 5032 upwardly. Accumulator pressure fluid (PA) is ported therefrom to the bottom of the reverse motion latch piston 5178 while the top side is directed to tank pressure T. The reverse motion latch 5160 is thus moved upwardly in a retract position by hydraulic pressure fluid.

Accumulator pressure fluid is injected through a check valve 5127 into cavity below the restraining motion buffer piston 5124. Accumulator fluid pressure also holds the reverse motion latch piston detent 5180 disengaged.

In moving the reverse motion latch 5160 upwardly, it contacts the differential pivot 5146 thus holding the differential pivot 5146 and bringing both shoe indicator plungers 5152 up. In this action, the differential link 5142 is raised jointly by the differential pivot 5146 and the reverse motion latch piston 5178. The forward latch links 5120, 5122 are latched over-center in the forward-latch detent 5154.

50 The missile weapon 400 is moved into position on the guide arm 5002 by the loader saddle cart 2006 until the forward surface of the aft shoe 204 contacts the forward motion restraining latch 5118, as shown in FIG. 6. The forward motion pawl 2007 of the saddle cart 2006 then 55 slides between the reverse motion latch 5160 and the forward motion restraining latch 5118 and is partly encompassed by the swivel track 5144.

As shown in FIG. 7, a signal energizes a solenoid LCRA1 to shift directional valve 5036 and reverse hydraulic pressure on piston 5178. The reverse motion latch 5160 is then hydraulically lowered which brings the shoe indicator plungers 5152 on top of the aft shoe 204 where they cannot further extend. This causes a clockwise rotation of the differential link 5142.

65 Through the rearward shifting of the differential transfer clevis 5148, the track toggle link 5150 lifts the swivel track 5144. A chain pawl roller 2235, which is attached to the saddle cart forward motion pawl 2007 and which is now within the swivel track 5144 raises, lifts the forward motion pawl 2007 over the shoe 204 and transfers the engagement of the aft shoe 204 from the saddle cart 2006 to the guide arm 5002.

70 The chain pawl roller 2235 also contacts the pawl indicator link 5168. This keeps the safety latch 5158 dis-

engaged as long as the forward motion pawl 2007 is in the position shown in FIG. 7.

It is to be noted that with the chain pawl roller 2235 holding the safety latch 5158 off, a provision is thus made to be able to lift the reverse motion latch, and drop the forward motion pawl 2007 to countermand the loading of the missile weapon 400 and to retract it with the saddle cart 2006.

The reverse motion latch 5160 travels at an angle from the vertical. Guided in this matter, the latch 5160 actually wedges the aft shoe 204 against the forward motion restraining latch 5118.

The aft shoe latching mechanism 5110 is now holding the aft shoe 204 of the missile weapon 400 in the ready-to-fire position, shown in FIG. 8. The saddle cart 2006 is retracted from the guide arm 5002. The pawl indicator link 5168 then drops to lock the safety latch 5158 over the reverse motion latch 5160.

In FIG. 9, the booster 200 of the missile weapon 400 then fires and the booster aft shoe 204 has moved $\frac{3}{16}$ inch. The forward motion restraining latch 5118 restrains the forward motion of the aft shoe 204 with approximately 10,000 pounds of force for this portion of travel. Rotation of the forward motion restraining latch 5118 is resisted by the spring 5116 acting through the forward latch links 5120 and 5122.

The forward latch links 5120 and 5122 are travelling up, and, at the same time, are forced out over-center by the forward latch link cam 5140. When the links 5120 and 5122 are beyond the in-line position, they will collapse. FIG. 9a shows how the link 5120 rides up and to the right to clear the forward latch detent 5154.

The aft shoe 204 now moves forward 5.5 inches, as shown in FIG. 10. The forward motion restraining latch 5118 is shown against a buffer pad 5121, while the buffer piston 5124 restrains the recoil of the restraining motion spring 5116. The spring-loaded indicator plungers 5152 then drop, and aided by the hydraulic actuator piston 5174, the swivel track 5144 is lowered as the clevis 5148 shifts forward.

The aft shoe 204 then moves out of the aft shoe latching mechanism 5110, which now stabilizes, as shown in FIG. 11. The weight of the forward motion restraining latch 5118 pulls the forward latch links 5120 and 5122 in line.

The restraining latch 5118 probably goes through some violent motion. These motions may or may not snap the toggle links 5120 and 5122 into the forward latch detent 5154. The positive means of latching comes when the reverse motion latch 5160 is raised in readiness for another missile weapon 400, and the rocker arm 5130, pivoting against cam 5138, snaps the links 5120 and 5122 home in the detent 5154.

Obviously, many other modifications and variations of the present invention are possible in light of the above teachings. It is, therefore, to be understood that within the scope of the appended claims the invention may be practiced otherwise than as specifically described.

What is claimed is:

1. In a guided missile weapons system comprising a missile, a missile launcher, and means to convey the missile from storage and position it on said launcher, the improvement comprising, shoe means mounted on said missile and utilized for handling said missile, said shoe means having a forward and a rearward surface,

a saddle cart having a forward motion pawl which is operable to engage and disengage said forward surface thereby preventing relative forward motion of said missile when engaged, said cart having a reverse motion pawl operable to engage and disengage said rearward surface thereby preventing relative rearward motion of said missile when engaged, said cart being operable to engage said missile launcher in a manner to permit transfer of said missile from said cart to said launcher, a forward motion latch means and a reverse motion latch means operably mounted on said missile launcher, automatic means operable to effect engagement of said forward motion latch means with said forward surface when said cart is engaged with said launcher, said automatic means being operable to effect engagement of said reverse motion latch means with said rearward surface when said cart is engaged with said launcher, said automatic means being operable to effect disengagement of said pawls from said surfaces subsequent to the engagement of said latches with said surfaces, and said automatic means being operable to release said forward motion latch means when a predetermined force is applied thereto.

2. The weapons system improvement set forth in claim 1 wherein said predetermined force is generated by said missile.

3. In a guided missile launching system of the type having a missile launcher and means to convey a missile from storage and position it on said launcher, said launcher having rail means mounted thereon and said missile being provided with at least one handling shoe engageable with said rail means and having forward and rearward surfaces, an improved shoe latching mechanism mounted on said launcher and comprising a pivotally mounted forward motion restraining latch and a slidably mounted, hydraulically actuated reverse motion restraining latch, spring means, over-centering linkage means interconnecting said spring means with said forward motion latch to lock said latch in its shoe engaging position, cam means operative to force said over-centering linkage means through its center position, whereby upon the exertion of a predetermined force by said shoe upon said forward motion latch, said spring means is overcome, allowing said cam means to trip said over-centering linkage, thereby releasing said forward motion latch, spring-biased safety latch means operative to lock said reverse motion restraining latch in its shoe-engaging position, slidably mounted shoe indicator means, differential linkage means interconnecting said shoe indicator means and said safety latch, whereby upon engagement of the shoe with said shoe indicator means, said differential linkage means is actuated to engage said safety latch with said reverse motion restraining latch, thereby locking the latter in its shoe engaging position.
